(57) **CLAIM**

The ornamental design for a liquid handling platform, as shown and described.

DESCRIPTION

FIG. 1 is an isometric view of a front, top, and left side of the liquid handling platform showing our new design;

FIG. 2 is a front elevational view of the liquid handling platform of FIG. 1;

FIG. 3 is a rear elevational view of the liquid handling platform of FIG. 1;

FIG. 4 is a left side elevational view of the liquid handling platform of FIG. 1;

FIG. 5 is a right side elevational view of the liquid handling platform of FIG. 1;

FIG. 6 is a top plan view of the liquid handling platform of FIG. 1; and,

FIG. 7 is a bottom plan view of the liquid handling platform of FIG. 1.

The broken lines are for the purpose of illustrating environmental structure and form no part of the claimed design. The portions of the liquid handling platform and cover having curved surface shading represent a translucent surface. Features and/or surfaces representing the inner workings of the liquid handling platform that would be visible behind the translucent surfaces form no part of the claimed design.
